[57] CLAIM

The ornamental design for golf club head, as shown and
described.

DESCRIPTION

FIG. 1 is a front elevational view of a golf club head
incorporating my new design, the shaft shown in phan-
tom lines being for reference purposes only and not
comprising part of the design.

FIG. 2 is a left side elevational view.

FIG. 3 is a right side elevational view.

FIG. 4 is a top plan view.

FIG. 5 is a bottom plan view.

FIG. 6 is a rear elevational view.

FIG. 7 is a perspective front top right side view.

FIG. 5

FIG. 7

FIG. 6
